UNITED STATES PATENT OFFICE.

JOHN MAGEE, OF CHELSEA, MASSACHUSETTS, ASSIGNOR TO THE MAGEE FURNACE COMPANY.

DESIGN FOR A PORTABLE COOKING-RANGE.

Specification forming part of Design No. 5,863, dated May 21, 1872.

To all whom it may concern:

Be it known that I, JOHN MAGEE, of Chelsea, in the county of Suffolk and State of Massachusetts, have invented a new Design for a Portable Cooking-Range, of which the following is a full, clear, and exact description, reference being had to the accompanying drawing making part of this specification.

My invention consists in a design for a portable cooking-range, the rear of the top plate of which projects out from the back to form a base, upon which to support an elevated hot closet, in which to keep articles of food warm after being cooked.

In the said drawing, A is a portable cooking-range, supported on legs 2. The rear of the top plate a of this range projects over beyond the line of the back b, in order to form a base for supporting an elevated hot closet, B, in which to keep warm the articles of food cooked in or on the range. The tops of the

standards c, supporting the front d of the closet, project slightly in front of the bottoms of the standards; and below the front plate of the closet an open space, f, is left to allow of the convenient handling of the utensils to be used in the holes in the top plate. The front of the hot closet is provided with one or more swinging or sliding doors, h; the whole design being unique, ornamental, and useful.

Claim.

What I claim as my invention, and desire to secure by Letters Patent, is—

The design for a portable cooking-range, substantially as herein shown and described.

Witness my hand this 27th day of March, 1872.

JOHN MAGEE.

In presence of—

N. W. STEARNS,
W. J. CAMBRIDGE.
